UNITED STATES PATENT OFFICE.

JERROLD F. WALTON, OF STURGIS, MICHIGAN.

ADJUSTABLE CHAIR.

1,184,902.

Specification of Letters Patent.

Patented May 30, 1916.

Application filed November 22, 1915. Serial No. 62,776.

To all whom it may concern:

Be it known that I, JERROLD F. WALTON, a citizen of the United States, residing at Sturgis, county of St. Joseph, State of Michigan, have invented certain new and useful Improvements in Adjustable Chairs, of which the following is a specification.

This invention relates to improvements in adjustable chairs.

10 My present improvements relate particularly to adjustable chairs of the type shown in the patent to Borgert, No. 1,087,526, February 17, 1914, and is in some respects a modification of and improvement upon the 15 structure there shown.

The main objects of my present invention are: First, to provide in an adjustable chair an improved means for adjustably supporting the back. Second, to provide in an adjustable chair an improved means for adjustably supporting the back in which the parts are simple and economical to produce, easily assembled and strong and durable, and at the same time a structure which is 25 easily operated.

Further objects, and objects relating to structural details, will definitely appear from the detailed description to follow.

I accomplish the objects of my invention 30 by the devices and means described in the following specification.

The invention is clearly defined and pointed out in the claims.

A structure which is a preferred embodiment of my invention is clearly illustrated 35 in the accompanying drawing, forming a part of this specification, in which:

Figure I is a detail plan view of a structure embodying the features of my invention. Fig. II is a detail vertical section on a line corresponding to the broken line 2—2 of Fig. I, parts being shown in full lines for convenience in illustration. Fig. III is an enlarged detail vertical section corresponding to that of Fig. II, showing the relation of the pawl to the adjustable rack and pawl actuating means. Fig. IV is an enlarged perspective view of the locking pawl. Fig. V is an enlarged detail vertical 50 section on a line corresponding to line 5—5 of Fig. I, showing details of the actuating means. Fig. VI is an enlarged detail section on a line corresponding to line 6—6 of Fig. II. Fig. VII is a detail section of a 55 slightly modified structure.

In the drawing similar reference charac-

ters refer to similar parts throughout the several views, and the sectional views are taken looking in the direction of the little arrows at the ends of the section lines.

60

Referring to the drawing, 1 represents the front legs and 2 the rear legs. The legs are connected by the side rails 3, front rails 4 and rear rails 5, thus forming the main frame of the chair.

65

The back, designated generally by the numeral 6, is pivotally mounted on the frame, as is common in chairs of this type. The seat is designated generally by the numeral 7. As the details of the back and seat 70 form no part of my present invention they are not further described herein.

The back adjusting and supporting means comprise the supporting bar 8, channel-shaped in cross section to provide spaced 75 side members 9. The supporting bar 8 is provided with attaching ears 10 at its front end and is bifurcated or provided with diverging arms 11 at its rear end. The supporting bar is disposed to face downwardly 80 and is secured at its front end to the inner side of the front rail 4 of the frame and at its rear end to the rear rail 5.

The back is provided with an arm 13 projecting downwardly in front of the rear rail 85 5 to swing between the arms 11 of the supporting bar. A rack bar 14 is disposed within the supporting bar to face downwardly therein and is pivotally connected at 15 to the lower end of the arm 13 of the 90 back. At its front end the rack bar 14 is provided with a cross pin 14' disposed through the longitudinal slots 16 in the side members of the supporting bar. This pin 95 slidably supports the front end of the rack bar. The slots are of such width as to allow a limited lateral movement of the rack bar, thus preventing binding.

A bearing projection 17 is formed in the top of the supporting bar so that the rack 100 bar bears thereon and friction is reduced.

The pawl 18 is mounted below the rack bar on the pivot 19 extending between the side members of the supporting bar to contact with the rack. The pawl is actuated to 105 and supported in rack engaging position by means of the actuating member 21 having a cam 22 adapted to coact with the pawl. The actuating member is slidably supported in holes in the side members of the supporting bar so that when in its actuated position it locks the pawl in engagement with 110

the rack. When the actuating member is retracted the pawl falls from the rack and the rack bar is released. The actuating member, in the structure illustrated, is in the form of a rod and is pivotally connected at 23 to the bell crank lever 24, which is mounted on the pivot 25 on the cross bar 26, the inner end of which is secured to the supporting bar by the rivet 20 and which extends from the supporting bar to one of the side rails of the frame.

10 A push rod 27 having a button 28 is disposed through the arm 29 of the chair for actuating the bell crank and through it the pawl actuating member 21.

15 A spring 30 is connected at one end to the bell crank lever 24 and at the other to the cross bar 26 and normally holds the actuating member in its pawl engaging position.

20 When the actuating member is in its actuated position as shown in Fig. III, the pawl is locked in engagement with the rack securely supporting the back in its adjusted 25 positions.

To release the back it is only necessary to push downwardly on the button 28, which retracts the actuating member releasing the pawl and freeing the rack bar.

30 The back is automatically returned to its upright position by means of the coiled springs 31 which are connected at their forward ends to the cross pin 14' and at their rear ends to ears 32 struck out from the 35 arms 11 of the supporting bar.

35 In the modified structure shown in Fig. VII the rack bar 33 is connected to the arm 13 of the back by means of the link 34. The teeth of this rack are faced forwardly and the pawl 35 is correspondingly modified. In other respects the structure is the same as that described. By thus forming and arranging the parts they are simple and economical to produce and easily 45 assembled and at the same time the structure is easily operated and very secure.

40 I have illustrated and described my improvements in detail in the form in which I have embodied the same. I have not attempted to illustrate or describe certain 50 modifications which I contemplate as I believe the disclosure made will enable those skilled in the art to which my invention relates to embody or adapt the same as may be desired. I desire, however, to be understood as claiming my improvements specifically in the form illustrated as well as broadly within the scope of the appended 55 claims.

60 Having thus described my invention, what I claim as new and desire to secure by Letters Patent, is:

1. In a chair, the combination with a frame comprising front, side and rear rails 65 and an adjustable back, a channel-shaped

supporting bar having diverging arms at its rear end and attaching ears at its front end disposed between and secured to the front and rear frame rails facing downwardly, the sides of said supporting bar being longitudinally slotted, a downwardly projecting arm on said back disposed to swing between said supporting bar arms, a rack bar disposed within said supporting bar to face downwardly and pivotally connected to said arm on said back, a cross pin at the forward end of said rack bar projecting through said slots in said supporting bar, a pawl pivotally mounted within said supporting bar below said rack bar to 80 coact therewith, a reciprocating actuating member slidably arranged through said supporting bar below said pawl and provided with a cam for actuating the pawl, means for retracting said actuating member, an actuating spring for said actuating member, and springs connected to said cross pin and to said arms of said supporting bar.

2. In a chair, the combination with a frame comprising front, side and rear rails and an adjustable back, a channel-shaped supporting bar having diverging arms at its rear end and attaching ears at its front end disposed between and secured to the front and rear frame rails facing downwardly, the sides of said supporting bar being longitudinally slotted, a downwardly projecting arm on said back disposed to swing between said supporting bar arms, a rack bar disposed within said supporting bar to face downwardly and pivotally connected to said arm on said back, a cross pin at the forward end of said rack bar projecting through said slots in said supporting bar, a pawl pivotally mounted within said supporting bar below said rack bar to coact therewith, and a reciprocating actuating member slidably arranged through said supporting bar below said pawl.

3. In a chair, the combination with a frame comprising front, side and rear rails and an adjustable back, a channel-shaped supporting bar having diverging arms at its rear end and attaching ears at its front end disposed between and secured to the front and rear frame rails facing downwardly, the sides of said supporting bar being longitudinally slotted, a rack bar disposed within said supporting bar to face downwardly and operatively connected to said back, a cross pin at the forward end of said rack bar projecting through said slots in said supporting bar, a pawl pivotally mounted within said supporting bar below said rack bar to coact therewith, a reciprocating actuating member arranged through said supporting bar below said pawl, and springs connected to said cross pin and to said arms of said supporting bar.

4. In a chair, the combination with a

frame and an adjustable back, of a channel-shaped supporting bar mounted on said frame to face downwardly, a downwardly projecting arm on said back, a rack bar 5 slidably supported within said supporting bar to face downwardly and pivotally connected to said arm on said back, said supporting bar having a bearing at the top for said rack bar, a pawl pivotally mounted 10 within said supporting bar below said rack bar to coact therewith, and a reciprocating actuating member arranged through said supporting bar below said pawl.

5. In a chair, the combination with a frame and an adjustable back, of a channel-shaped supporting bar mounted on said frame to face downwardly, a rack bar 15 slidably supported within said supporting bar to face downwardly and operatively connected to said back, a pawl pivotally mounted within said supporting bar below said rack bar to coact therewith, a reciprocating actuating member arranged through said supporting bar below said pawl and 20 provided with a cam for actuating said pawl, means for retracting said actuating member, and an actuating spring for said actuating member.

6. In a chair, the combination with a frame and an adjustable back, of a supporting bar comprising spaced side members 25 mounted on said frame, a rack bar slidably supported between said supporting bar side members to face downwardly and operatively connected to said back, a pawl pivotally mounted between said supporting bar side members below said rack bar to coact therewith, and a reciprocating actuating member arranged through said supporting 30 bar below said pawl and adapted to support said pawl in its engaging and disengaging positions.

7. In a chair, the combination with a frame and an adjustable back, of a supporting bar comprising spaced side members 45 mounted on said frame, a rack bar slidably supported between said supporting bar side members to face downwardly and operatively connected to said back, a pawl pivotally mounted between said supporting bar 50 side members below said rack bar to coact therewith, and a reciprocating actuating member arranged through said supporting bar below said pawl.

8. In a chair, the combination with a frame and an adjustable back, of a channel-shaped supporting bar mounted on said frame to face downwardly, a rack bar 55 slidably supported within said supporting bar to face downwardly and operatively connected to said back, a pawl pivotally mounted within said supporting bar below said rack bar to coact therewith, and means for actuating said pawl adapted to normally lock it in engagement with the rack.

9. In a chair, the combination with a frame and an adjustable back, of a supporting bar comprising spaced side members mounted on said frame to face downwardly, a rack bar 60 slidably supported between said supporting bar side members to face downwardly and operatively connected to said back, a pawl pivotally mounted between said supporting bar side members below said rack bar to coact therewith, and means for actuating 65 said pawl adapted to normally lock it in engagement with the rack.

In witness whereof, I have hereunto set my hand and seal in the presence of two witnesses.
